Primary Examiner — Wan Laymon*Assistant Examiner* — Mark Booker(74) *Attorney, Agent, or Firm* — Fitch, Even, Tabin & Flannery LLP(57) **CLAIM**

We claim the ornamental design for a personal hygiene aid part, as shown and described.

DESCRIPTION

FIG. 1 is a perspective view of a personal hygiene aid part showing our design;

FIG. 2 is a left side elevation view thereof;

FIG. 3 is a right side elevation view thereof;

FIG. 4 is a front side elevation view thereof;

FIG. 5 is a rear side elevation view thereof;

FIG. 6 is a top side elevation view thereof; and,

FIG. 7 is a bottom side elevation view thereof.

The broken lines shown in the figures represent portions of the personal hygiene aid part that form no part of the claimed design.
